UNITED STATES PATENT OFFICE

2,621,230

POLARITY INDICATOR

Anders Einar Andersson, Minneapolis, Minn.

Application November 10, 1948, Serial No. 59,251

2 Claims. (Cl. 175—183)

1

My invention relates to an improved polarity indicator for determining the polarity of electromagnetic fields.

As is well known, electric machines of the general class of motors and generators, have as an essential part of their operating mechanism a number of electrical windings used to produce electromagnetic force. In various arrangements, these windings are disposed about a central axis of a part of the machine, and to be effectively disposed, those windings which produce a positive electromotive force must be alternately disposed with relation to those which produce a negative electromotive force. In assembling machines of this type, the mechanic or operator who is engaged in the assembling operation cannot distinguish the positive and negative windings merely by their appearance and must, therefore, rely on some other means to determine the polarity of each of the elements, as otherwise the parts are apt to be assembled in such a manner as to render the machine inoperative.

There have been several known devices for indicating polarity of electromagnetic fields, some of which are relatively complex and require some form of manual manipulation. The most commonly accepted simple indicating device has been a magnetic compass. The use of a compass, however, can become unsatisfactory after a certain amount of use because the magnetism of the needle can be materially affected by the magnetic effect of the fields so that it is no longer dependable.

I have discovered a relatively simple device for determining the polarity of electromagnetic fields, which is certain in operation and which does not require any form of manual manipulation of the indicating mechanism. The present invention includes as an essential element an armature mounted within a casing and supported by bearing means which will permit its free axial movement. The casing has connected thereto a rigid conductor in the form of a steel rod which may be placed in contact with an electromagnetic field to form a conducting path from the field to the armature so as to attract or repel one end of the armature thereby causing the armature to rotate on its bearing support. In order to stabilize the armature against uncontrolled movement and to further maintain well established magnetic poles at the opposite ends of the armature, one or more permanent magnets are contained within the casing with their opposite poles spaced from either end of the armature so that the armature is always within the magnetic path between the opposite poles of the magnet. An indicating needle is secured to the armature or its bearing support, and this needle is movable with respect to a printed index carried by the casing and having indicia thereon to indicate the

2

positive and negative poles, to one of which the needle will be moved when the aforementioned rod is brought in close proximity to an electromagnetic field. Spring means are secured to the bearing support for the armature and the indicating needle, to return the needle to a neutral position when the device is inactive.

An important advantage of the invention is that a unitary structure is provided which does not require manual manipulation. Moreover, the indicating needle does not wobble in uncontrolled movement as in the instance of a magnetic compass since the armature is constantly subject to the lines of magnetic force passing from the opposite poles of the adjacent permanent magnet. Furthermore, the fine hair spring also acts to stabilize the armature against uncontrolled movement and to immediately return it to a neutral position.

An object of the invention is to provide a relatively simple and effective device for indicating the polarity of an electromagnetic field.

Another object is to provide a polarity indicator which includes a casing containing an armature supported for axial rotation, which armature is mounted within the casing on one side of the central axis thereof, and a rigid rod secured to a side of the casing nearest the armature for conducting magnetic flux from an electromagnetic field to the casing in such a manner as to attract one end of the armature, together with indicating means cooperable with the armature for indicating the polarity of the electromagnetic field.

A further object is to provide a polarity indicator which includes an armature formed of substantially rectangular configuration which is supported within a casing adjacent one side thereof by means which will permit free axial movement of the armature, together with a metallic conductor secured to the casing and adapted to form a path for magnetic flux from an electromagnetic field to the casing to attract one end of the armature, and a permanent magnet positioned within the casing and having its opposite poles spaced on either side of the armature so that the armature is positioned in the magnetic field of the magnet and is stabilized by the magnet.

Other and further objects may become apparent from the following description and claims, and in the appended drawing in which:

Fig. 1 is a general exterior view of the invention;

Fig. 2 is a section taken on the lines 2—2 of Fig. 3, showing on an enlarged scale the interior of a portion of the device shown in Fig. 1;

Fig. 3 is an enlarged vertical section taken on the lines 3—3 of Fig. 2; and,

Fig. 4 shows the manner in which the invention is applied to an electromagnetic field of an

electric machine for determining polarity of the field.

Referring now to the several views of the drawing, general reference numeral 10 indicates a polarity indicator and includes a casing 12 of cylindrical configuration which, as indicated in Fig. 3, is hollow and is enclosed on its forward face by a transparent window 14.

As best shown in Fig. 3, within the interior of casing 12 is an inner casing 16 which is clamped to the forward edge of casing 12 by a ring 18. As seen in Figs. 2 and 3, a plate 20 is secured to casing 16 by a nut and bolt arrangement 22. Plate 20 has a tapered extension 24 which terminates in an upstanding bracket 26. A second plate 28 which is secured to casing 16 by a nut and bolt arrangement 30 is also provided with a tapered extremity 32 that forms a continuation of bracket 26. A bearing rod 34 seen in Fig. 3 is supported between the outer end of bracket 26 and an inner portion of the tapered end 24 of plate 20. A fine coil spring 36 is wound about bearing 34 and secured to the tapered portion 24 of plate 20 for purposes to be described hereinafter relative to maintaining bearing 34 in a fixed position against axial rotation.

An armature 38 which is of rectangular configuration is supported on bearing 34 with its opposite ends extending horizontally with respect to the horizontal axes of the casing, and the same is, as clearly shown, situated beneath the central horizontal axes of the casing and adjacent the lower portion of the casing. A first arcuate shaped permanent magnet 40, shown in dotted lines in Fig. 2, is supported within the base of casing 16 underneath a layer of insulation 41 and has its opposite poles spaced on either side of the ends of armature 38. A second arcuate shaped permanent magnet 42 is mounted within casing 16 and also has its opposite poles indicated in Fig. 2 at 43 and 44 spaced on opposite sides of armature 38. While the device is effective when only one permanent magnet is used, I have found that the armature is more stable when two magnets are used because of the greater amount of magnetic force which is applied by the combined action of magnets 40 and 42. It is essential to state at this point that the respective poles of the two magnets 40 and 42 on each side of the armature are of the same polarity so that I believe the effect is substantially the same as that which would be obtained if one magnet of stronger force were used in place of the magnets 40 and 42.

Also secured on bearing 28 is a needle 46 which is visible through an aperture 48 in a disk 50 as seen in Fig. 1. The disk 50 carries printed indicia thereon and shown as the letters N and S to indicate positive and negative polarity.

A rigid rod 52, formed of a low permeable ferrous material such as steel, extends through casing 12 and is rigidly secured to casing 16 by a nut and bolt arrangement shown at 54 in Figs. 2 and 3. It is important to point out that rod 52 is secured to casing 16 immediately beneath the center of armature 38.

Referring now to Fig. 4 is shown the portion of an electric machine here designated as a motor 56 having a first field winding 58 and diametrically opposite thereto another field winding 60 which would presumably be of opposite polarity from winding 58. The device indicated by general reference numeral 10 is utilized to determine the polarity of poles 58 and 60 by plac-

ing rod 52 within the magnetic field of each of the field windings.

The operation of the device will now be explained. Referring to Fig. 4, the device 10 is shown in the manner in which it is applied to winding 60 with the rod 52 in contact therewith. When rod 52 is brought into the proximity of the electromagnetic field of winding 60 the magnetic flux is conducted through rod 52 to casing 16 adjacent the center of armature 38. Armature 38 is normally situated between the magnetic poles 43 and 44 of magnet 42 and similar poles of magnet 40 and, therefore, it is within the magnetic field of these magnets and will have positive and negative poles at its opposite ends. The permanent magnets are not essential to the operation of the device, but they do tend to stabilize the armature against uncontrolled wobbling movement. If the field of winding 60 is of positive polarity the armature 38 will rotate in a counterclockwise direction on bearing 26 and cause the needle 46 to move in the direction of the N indicia on disk 50; whereas if the polarity is opposite, the needle will be moved in the direction of the S indicia. The rod 52 merely acts as a conductor of the magnetic flux to a point immediately below the central axis of the armature. Of course, the magnetic effect of fields 58 and 60 are many times greater than magnets 40 and 42 and will, therefore, instantly overcome the effect of these magnets. However, when rod 52 is taken away from fields 58 or 60, the magnets 40, 42 aided by the resilience of spring 36 will immediately return the armature to its normally horizontal position where it will again form a path between the opposite poles of these magnets so that it will not be affected by any residual magnetism resulting from use. Since the device would be used on fields of differing polarity, rod 52 being formed of low permeable metal will not carry any considerable amount of residual magnetism. I have found that repeated use in fields of one type of magnetism does not leave rod 52 carrying sufficient residual magnetism to have any effect on armature 38.

My invention is not restricted to the single illustration but is defined in the terms of the appended claims.

I claim:

50 1. A device for indicating polarity of a magnetic field, comprising a casing, a linear magnetized armature centrally pivoted in the casing for rotative movement, at least one permanent magnet having portions of opposite polarity on either side and spaced from the ends of the armature, and a low permeable ferrous rod connected at one end to the casing at one side of and in spaced relation to the centrally pivoted portion of the armature to conduct magnetic flux from a magnetic field and thereby attract one end of the armature to indicate the polarity of the field by the direction of movement of the armature.

65 2. A device for indicating polarity of a magnetic field, comprising a casing, a magnetized armature of linear configuration, a bearing rod within said casing at one side of the center thereof supporting said armature for rotative movement, resilient means connected to the bearing rod for resisting rotative movement of the armature, a permanent magnet carried by the casing and having its opposite poles spaced from and in alignment with the opposite ends of the armature to stabilize the armature against rotative movement, a flux conductor consisting of a rigid ferrous rod of low permeability secured at

its inner end to the casing on a side thereof nearest the armature and at right angles to the rotative axis of the armature, said rod being adapted to conduct magnetic flux from an electromagnetic field to the interior of the casing to attract one end of the armature, and an indicating means connected with the armature and co-operable with an indicia carried by the casing for indicating the polarity of the field when one end of the armature is attracted to the inner end of the rod.
